UNITED STATES PATENT OFFICE.

GEORGE JOHN WOHLTMANN, OF NEW YORK, N. Y.

REAR-END SIGNAL FOR VEHICLES.

1,123,454.

Specification of Letters Patent.

Patented Jan. 5, 1915.

Application filed February 24, 1913. Serial No. 750,206.

To all whom it may concern:

Be it known that I, GEORGE J. WOHLTMANN, a citizen of the United States, and a resident of the city of New York, borough 5 of the Bronx, in the county and State of New York, have invented a new and Improved Rear-End Signal for Vehicles, of which the following is a full, clear, and exact description.

10 Among the principal objects which the present invention has in view are: to provide a signal of the character designated, the operation of which is simple, efficient and concordant with the movement of the 15 hand of the driver or traffic manager; to provide a simple and economical construction; and to provide a signal arranged to show, under all conditions, the rear-end or danger light.

20 One embodiment of the present invention is shown in the accompanying drawings, in which—

Figure 1 is a perspective view of a rear-end signal apparatus constructed and arranged in accordance with the present invention; Fig. 2 is a front view of the same, the cover being removed to expose the illuminating chambers; Fig. 3 is a vertical section taken on the line 3—3 in Fig. 2; 30 Fig. 4 is a horizontal section taken on the line 4—4 in Fig. 2; Fig. 5 is a detail view showing a fragment of the steering post of an automobile, having attached thereto a switch-box constructed and arranged in accordance with the present invention; Fig. 6 is a detail view in perspective of the switch box above mentioned, the wall of said box being partly cut away to disclose the interior and the telltale lamp mounted therein; 40 Figs. 7, 8 and 9 are views showing the three operative positions of the signal, indicating in the order named, the intention to effect a turn to the left, a turn to the right, and to stop; Fig. 10 is a diagrammatic view showing the electric wiring and arrangement of 45 signal lines therefor.

As seen in the drawings, a case or box is provided, having illuminating chambers 15, 50 16 and 17, grouped about and radiated from a central opening 18. The chambers recited are totally inclosed, and where desired, the backs thereof are coated with light-reflecting material of any suitable form. The chambers 15, 16 and 17 and the opening 18 are closed by a cover 19 which is provided with transparent or translucent colored sec-

tions or a glow pattern, shaped to form hands 20, 21 and 22, and a connecting wrist portion 23, said wrist portion being universal to all of the hands. Any suitable material, such as colored isinglass, celluloid, or glass, may be employed.

In the preferred form of apparatus, the glow pattern having the hands and wrist is formed of red or ruby glass, as the portion 60 forming the wrist 23 is constantly illuminated to serve as the rear-end signal or riding light of the vehicle. The apparatus is mounted in any suitable manner and in any convenient position at the rear of the vehicle.

Extending below and in line with the rear wall of the case is a panel 24, on which is placed the license number belonging to the vehicle. The face of the panel is illuminated by an electric lamp 25 which is mounted on a partition 26. The partition 26 forms the top of the chambers 15 and 16, and closes the end of the chamber 17. The bottoms of the chambers 15 and 16 are 75 formed by a narrow partition 27, the inner edge whereof is removed from the back of the casing and from the face of the panel 24. Directly above the opening or space left between the partition 27 and the panel 24, the lamp 25 is placed, from whence it 80 casts a light directly upon, to illuminate, the face of said panel 24.

The lamp 25 is constantly lighted when the switch 28 is closed to complete the circuit of said lamp through a battery 29 or other suitable source of electric current. The lamps 30, 31 and 32 are each illuminated when the push-buttons 33, 34 or 35 are depressed to complete the individual 90 circuits through said lamps and the battery 29. The buttons 33, 34 and 35 are each mounted upon a switch-box 36. The switch-box 36 is held permanently to a steering post 37, as seen best in Figs. 5 and 6 of the 100 drawings, by means of a strap or collar 38. The collar 38 carries a butterfly nut 39 and a screw stud 40. The box 36 is provided with a slotted tab 41, through the 105 end of which is inserted the stud 40, the sides of said tab extending below the nut 39. When said nut is manipulated, it will be seen that it operates to lock the collar 38 and tab 41 in fixed relation. The box 36 is provided with an orifice 42, below 110 which is placed a telltale lamp 43. The lamp 43, as shown in Fig. 10 of the draw-

ings, is common to all of the circuits incorporating the push buttons 33, 34 and 35. Therefore, when any of said buttons are depressed, and until released, the lamp 43 5 thrusts a light upward into view of the driver of the vehicle. Thus provision is made against the negligence of the driver in permitting a signal to remain at the rear of the vehicle after having acted in accordance with the signal; or in other words, the continuance of illumination of the lamp 43 operates to advise the driver of the fact that a signal is set.

Having thus described my invention, I 15 claim as new and desire to secure by Letters Patent:—

1. A signal as characterized, comprising a containing case having a cover, said cover being provided with transparent sections laterally extended and centrally united to indicate opposite lateral directions; a plurality of illuminating members for said sections; a plurality of partitions confining a central portion to exclude the light thereof 20 from the other portions; and means for selectively illuminating the said members.

2. A signal as characterized, comprising a central box-like structure having opaque sides; an electric lamp mounted in said box-like structure continuously illuminated; a plurality of elongated box-like structures adjacent to the central box-like structure and radiating therefrom; a plurality of electric lamps mounted in said elongated box-like structures; means for selectively illuminating the lamps in said elongated structures; and a cover for all of said box-like structures, said cover having transparent sections, the design of the section over the central box-like structure incorporating with the design of each of the other sections, when said other sections are illuminated, the section over said central structure also independently forming a design distinct from the other designs. 40 45

In testimony whereof I have signed my name to this specification in the presence of two subscribing witnesses.

GEORGE JOHN WOHLTMANN.
